UNITED STATES PATENT OFFICE.

LEWIS WEHNER, OF MADISON, WISCONSIN.

EQUALIZING SYSTEM FOR STEAM-SHOVELS AND THE LIKE.

1,075,178.

Specification of Letters Patent.

Patented Oct. 7, 1913.

Application filed February 17, 1913. Serial No. 748,937.

To all whom it may concern:

Be it known that I, LEWIS WEHNER, a subject of the Emperor of Germany, residing at Madison, county of Dane, State of Wisconsin, have invented certain new and useful Improvements in Equalizing Systems for Steam-Shovels and the like; and I do hereby declare the following to be a full, clear, and exact description of the invention, such as 10 will enable others skilled in the art to which it appertains to make and use the same.

The invention relates to apparatus for compensating and equalizing the load on the several trucks of large portable machines, 15 such as steam shovels, pile drivers, derricks and the like, which are usually provided with four or more supporting trucks adapted to be propelled and operated upon four or more temporary tracks, which, because of 20 their temporary character, present many irregularities which would produce an objectionable shifting and irregular distribution of the load on the four trucks and consequent undue and unnecessary strains on the 25 apparatus as a whole, if no compensating means were provided to correct the difficulty.

As indicated, the present invention is designed to remedy the objections noted, in a simple and efficient manner, and further, to 30 provide means associated with the equalizing or compensating devices for firmly and rigidly supporting the machine on all of its trucks when the machine has been brought to position to perform its particular work.

35 It has been attempted heretofore to provide machines of the character indicated with hydraulic or pneumatic means to serve as absorbers or compensators for the irregularities in the trackway while the machine is 40 being propelled, and also to provide independent devices for shoring up and truing the machine when in working position, but such constructions have not been wholly satisfactory or effective for the purposes indicated, owing to the uncertain action of the 45 hydraulic or pneumatic compensators and the tendency of the same to become deranged, and for the further fact that the shoring or leveling devices have usually 50 been carried as separate demountable parts of the apparatus to be placed in position and adjusted only after the machine has been brought to the place of operation. According 55 to the present invention, however, these difficulties are completely obviated, and the

improved mechanical means for compensating for the irregularities in the trackway and for affording a rigid support for the body of the machine when the same is in working position perform their functions 60 with certainty and economy.

In furtherance of these objects, flexible equalizing means is provided by furnishing the machine with a transverse system of bell crank levers pivoted to the sub-base and connected by a reach rod, the ends of the bell crank levers being connected by suitable center bearings to the front truck frames so that the front trucks are capable of independent vertical movement due to irregularities in the tracks, which movement is taken up by the system of compensating levers without transmitting such movement to the sub-base and the machine supported thereby. The rear of the sub-base is mounted directly upon two rear trucks in such way as to allow the trucks to adapt themselves to local irregularities in the track without imparting the resultant motion to the sub-base. In order to provide for irregularities in the 70 rails supporting an individual truck, each of the four trucks is so constructed that its frame is supported on the two axles by a three-point bearing which will allow the axles to move in a vertical plane with respect 75 to each other and properly distribute the load of each truck on the four wheels thereof. The combination of the supporting means between the trucks and the sub-base and between the individual truck frames 80 and their axles results in a proper disposition of the entire load on the machine among the several trucks and to the wheels of each truck, notwithstanding the irregularities of 85 the various tracks, while the auxiliary supporting devices adjustably mounted between the compensating levers and the sub-base will admit of the rigid and stable support 90 from the machine when the latter has been adjusted to its working position.

100 In describing the invention in detail, reference is made to the accompanying drawings, in which the invention is shown as applied to a steam shovel supported for movement along a four-rail trackway by means 105 of four trucks. It will be understood, however, that the invention is applicable to all propelled machines having four traction members, whether said members be trucks or other devices for accomplishing the same re- 110

sults, and it will be understood that various changes and modifications in the apparatus may be made without departing from the spirit or scope of the invention.

5 In the drawings aforesaid, Figure 1 is a side elevation of the power portion of a steam shovel provided with a sub-base mounted on the supporting trucks in accordance with the invention. Fig. 2 is a front 10 elevation of the apparatus. Fig. 3 is a top plan view of a preferred form of front truck. Fig. 4 is a side elevation thereof.

Referring to Figs. 1 and 2, 1 indicates the sub-base of the machine 2, the character and 15 construction of which latter is immaterial to the present invention, but as illustrated takes the form of a standard type of steam shovel capable of revolving upon the sub-base and provided with suitable mechanism 20 for operating the shovel and for propelling the same along the trackway. Preferably, four trucks are employed for supporting the sub-base at its four corners, said trucks operating upon four rails, as indicated, which 25 latter are laid for temporary use and without any particular regard to regularity and level. The two rear trucks 3 directly support the rear portion of the sub-base and in order to permit each of said trucks to adapt 30 itself to local inequalities without imparting motion to the sub-base, each truck is connected to the sub-base by a center bearing, comprising a casting 27 which is carried by the frame 11 of the truck and a co-operating 35 casting 27' connected to the sub-base, and the truck frame is supported on the axles of the four wheels at only three points, as will be more fully described hereinafter. The two front trucks 4, 4, are also provided with 40 four wheels, the truck frame 11 having a three-point suspension on the two axles of the four wheels aforesaid. The frame 11 of each truck 4 is preferably formed as a relatively heavy casting having a centrally 45 disposed bearing socket 6', as indicated, in Figs. 3 and 4, and each of said sockets is engaged by a rounded boss or center bearing 6 secured to the out-board end of a bell 50 crank lever 5, which in turn is pivotally connected by heavy lugs 1' to the sub-base 1, as indicated in Figs. 1 and 2. Each of said bell crank levers 5 is pivoted to the sub-base laterally of the longitudinal axis of the latter and the pendent arms of said levers 5 are 55 connected together by a reach rod 5'.

As each of the four trucks is provided with four wheels that run on two trucks, it is desirable to construct the trucks so that the load will be distributed to the four wheels 60 of each truck in a manner similar to the distribution of the load to the four trucks. The general construction of the front and rear trucks is the same, with the exception that the rear trucks are provided with driving 65 gearing by means of which the appara-

tus is propelled along the tracks, as will be hereinafter described.

Figs. 3 and 4 illustrate the construction of the front trucks which, as indicated, is substantially like that of the rear trucks, except in the particulars noted. The four wheels 7 of each truck are provided with flanges on each side of the tread portions to retain the wheels on the rails constituting the trackway. Each pair of wheels is preferably keyed or otherwise made fast to the front and rear axles 9 and 10 respectively. A bearing frame or supporting member 11 is mounted on the two axles and is provided at its rear end with a single bearing 12 which 75 engages the journal 13 of the rear axle 10. The portion of the bearing 12 which engages the axle 10 is slightly curved or convexed longitudinally to allow the axle to tilt transversely of the truck. It is seen, therefore, that the said bearing frame 11 is supported on the rear axle only at a point intermediate the ends of the axle. To secure the bearing 80 in place and to hold the journal of the axle against the bearing 12, there is provided a bearing cap 13' which encircles the under side of the axle and is secured to the frame 11 in any suitable manner. Preferably, ribs 85 or projections 14 are cast integrally on the bearing frame 11 and one end of the bearing cap is secured to these ribs by suitable bolts and nuts 15 and 16. The other end of the cap is secured to the web portions 17 of the frame by similar bolts 18. The frame is supported on the front axle at two points 90 adjacent the wheels, the two bearings thus formed being provided with caps 13 generally similar to those associated with the rear axle, as clearly illustrated in Figs. 3 and 4 of the drawings. By this construction, it 95 will be apparent that the rear axle of each truck is free to tilt out of the normal horizontal plane of the four wheels and conversely, the four wheels may tilt or change 100 their plane without disturbing the position of the rear axle. Irregularities in the rails will consequently not tend to throw the load 105 on two wheels only of the truck, as would be the case if the three-point suspension system between the truck frame and the axles 110 were not employed. 115

Preferably, the rear trucks only are provided with driving means for propelling the machine along the trackway, which driving means comprises a shaft 21 journaled in the 120 truck frame 11 intermediate the two axles. A pinion 22 is secured to said shaft 21 and meshes with the toothed flanges 23 of the outside front and rear wheels, as indicated in Fig. 1. The shaft 21 is driven preferably 125 by a sprocket 26 located under the truck center so that the pull of the sprocket chain 25 upon the sprocket, does not tend to prevent the truck from swiveling when the entire machine strikes a curve in the track. 130

As illustrated, the sprocket wheel 26 of each rear truck is driven by a sprocket chain 25 which cooperates with the sprocket-wheel 28 on the end of a horizontal driven shaft 29 journaled transversely of the sub-base, said shaft having thereon a beveled pinion 30 meshing with a beveled gear 31 on a vertical shaft 32 located in the center of the sub-base and the pivotal axis of the super-structure, which shaft is driven by power mechanism carried by the super-structure.

From the foregoing description, it will be apparent that the machine when being propelled along the tracks will distribute its load not only to the four trucks, but to the four wheels of each truck. The three-point suspension of the individual trucks admits of the adjustment of the individual trucks wheels to irregularities of the track without disturbing the proper disposition of the load carried by each truck to the several wheels of the truck. The center bearing between the frames of the rear trucks and the sub-base likewise admits of an adjustment 25 of the truck as a whole to the track under it and serves to keep the two rear corners of the sub-base at the same height above their respective tracks, whether these tracks are or are not at the same elevation. The bell-30 crank system connecting the two forward trucks with the sub-base admits of the said forward trucks operating upon rails of different elevations without affecting the sub-base and, conversely, any angular change of 35 the sub-base, due to the rear trucks running on tracks of unequal elevation, will not be transmitted to the front trucks. The load is therefore distributed on the four trucks so that each truck will support its proper 40 proportion thereof irrespective of the unevenness or unequal elevation of the tracks. Furthermore, as each truck is provided with 45 a three-point suspension on its two axles, it is likewise capable of adapting itself to local inequalities existing in its track and to properly distribute its load to each of its four wheels. The conjoint operation of the several structural arrangements results in 50 the proper distribution of the entire load among all of the wheels supporting the apparatus, so that each wheel takes its proper proportion of the load and the machine may be safely propelled along irregular and uneven trackways without imposing undue 55 strains on any of the parts thereof.

If the two rails on one side of the trackway happen to be at a greater elevation than the two rails on the opposite side thereof, the bell-crank equalizer system will be tilted 60 to compensate for such difference in elevation, but the sub-base 1 retains its normal position and the load will be properly distributed to the four trucks. If, on the other hand, the four rails are substantially in the 65 same horizontal plane, but one rail of one

side of the trackway is elevated slightly above the adjacent rail, the truck engaging these two rails of unequal elevation will be tilted, but due to the center bearing connection with each truck frame, such tilting will 70 not be transmitted to the sub-base by the rear trucks or to the equalizer system by the front trucks. It is obvious that such inequalities of two adjacent rails would tend to throw the entire weight, which each truck 75 normally supports, on two of the wheels of such truck. This, however, is prevented by supporting each truck frame at three points only on the axles, as already described, so that local inequalities will not cause the four 80 wheels of each truck to be tilted in unison in the same horizontal plane, but only one axle of each truck is permitted to tilt in a vertical plane and such tilting will be effective to properly distribute the load carried 85 by each truck to each of the wheels thereof. It follows, therefore, that all inequalities of the trackway, whether such inequalities are relative to both sides of the track or to the two rails constituting one side of the 90 track, are effectively compensated and the weight is distributed not only to the four trucks but to the individual wheels of each truck.

When the machine is brought into position for operation, it is necessary that the sub-base and the super-structure be firmly supported against any tendency to tilt and, in many cases, the machine must be supported with the sub-base level. To effect 95 this object, it is proposed to provide each forward corner of the sub-base with a self-contained supporting and leveling device, which in the construction shown, takes the form of jack-screw 40, adjustably mounted 100 in the threaded nut 41 rigidly secured to the frame of the sub-base so that when the jack-screw is retracted, it will lie substantially within the frame of the sub-base, but when the said jack-screw is rotated to cause it to move downward in its threaded nut, the head portion thereof engages the upper face of the bell-crank lever, preferably in alignment with the center bearing 6, so that the front portion of the sub-base is rigidly 105 supported from the trucks and may be accurately adjusted to level position.

What I claim is:—

1. In a machine of the class described, provided with four supporting trucks, the 120 combination with the two supporting trucks at one end of the machine, of a direct flexible mechanical connection between said trucks, said connection adapted to permit one of the trucks to move upward and the 125 other to move simultaneously downward with relation to the machine body.

2. The combination with a machine of the 130 class described, mounted directly upon two rear trucks, of two front supporting trucks,

and compensating mechanism disposed between said front trucks and the forward portion of the machine.

3. The combination with a machine of the class described, mounted directly on two rear trucks, of two front trucks, an equalizer system comprising bell-crank levers and an intermediate reach rod supported by said front trucks, and connections between the respective bell-crank levers and the forward portion of the machine.

4. The combination with a machine of the class described, of four supporting trucks two of which directly support one part of the machine, an equalizer system comprising connected bell-crank levers supported by the other two trucks, and connections between said bell-crank levers and the other part of the machine.

20 5. The combination with a machine of the class described, of four supporting trucks two of which directly support one part of the machine, an equalizer system comprising two bell-crank levers and an interposed reach rod, center bearing connections between each of said bell-crank levers and one of the other trucks, and means for connecting said bell-crank levers with the other part of the machine.

30 6. In a machine of the class described provided with four supporting trucks, the combination with two of the trucks, of an equalizing system comprising two bell-crank levers and a reach rod connecting the same, said bell-crank levers being supported at their outer ends by the two trucks aforesaid, and means for supporting one portion of the machine from said equalizer system intermediate the ends thereof.

40 7. A support for machines of the character described, comprising four load supporting trucks, an equalizing system comprising two bell-crank levers and a connecting reach rod supported by center bearings on two of said trucks, and means for connecting the machine body directly to two of the four trucks and to said equalizing system intermediate the ends of the latter.

50 8. In a machine of the class described provided with four supporting trucks, the combination with flexible equalizing means associated with the two supporting trucks at one end of the machine whereby the weight of the machine is distributed between the 55 several supporting trucks independently of inequalities of the track, of means asso-

ciated with said trucks whereby the load on each truck is distributed to the wheels thereof independently of irregularities of the track.

60 9. The combination with a machine of the class described, of four supporting trucks each including load equalizing means, direct connections between two of said trucks and one part of the machine, and an equalizer system disposed between the machine and the other two trucks.

65 10. In a machine of the class described provided with four supporting trucks, an equalizer system disposed between two of the trucks and the machine body to permit vertical movement of the trucks relative to the machine body, and independent means for rigidly supporting the machine body from the two trucks aforesaid.

75 11. In a machine of the class described provided with four supporting trucks, an equalizer system disposed between two of the trucks and the machine body to permit vertical movement of the trucks relative to the machine body, and adjustable jack screws for rigidly supporting the machine body from the two trucks aforesaid.

80 12. In a machine of the class described provided with four supporting trucks, an equalizer system disposed between two of the trucks and the machine body to permit vertical movement of the trucks relative to the machine body, and adjustable jack screws carried by the machine body for rigidly supporting the machine body from the two trucks aforesaid.

85 13. In a machine of the class described provided with four supporting trucks two of which are directly connected to the machine body, an equalizer system disposed between the other two trucks and the machine body, said system comprising bell cranks connected by center bearings with the respective trucks, a reach rod between said bell cranks, connections between each of said bell cranks and the machine body, and jack screws carried by the machine and adapted to be adjusted to afford a rigid support between the machine body and the trucks associated with equalizing means.

90 In testimony whereof I affix my signature, in presence of two witnesses.

LEWIS WEHNER.
